[57] CLAIM

The ornamental design for a vehicle exterior sun visor, as shown and described.

DESCRIPTION

FIG. 1 is a perspective view of a vehicle exterior sun visor in accordance with the present invention, it being understood that the broken lines showing a vehicle are for illustrative purposes only and form no part of the design; FIG. 2 is a perspective view of the vehicle exterior sun visor of the invention, alone;

FIG. 3 is a top view of the vehicle exterior sun visor of FIG. 2;

FIG. 4 is a front view of the vehicle exterior sun visor of FIG. 2;

FIG. 5 is a back view of the vehicle exterior sun visor of FIG. 2; and,

FIG. 6 is a right side view of the vehicle exterior sun visor of FIG. 2, it being understood that the left side view is a mirror image of the right side view.
